JOSEPH KARL SCHWARZER, OF SYRACUSE, NEW YORK.

CLEAT ATTACHMENT FOR FOOTBALL-SHOES.

1,391,346.

Specification of Letters Patent. Patented Sept. 20, 1921.

Application filed April 26, 1921. Serial No. 464,658.

To all whom it may concern:

Be it known that I, JOSEPH K. SCHWARZER, of Syracuse, in the county of Onondaga, in the State of New York, have invented new and useful Improvements in Cleat Attachments for Football-Shoes, of which the following, taken in connection with the accompanying drawings, is a full, clear, and exact description.

This invention relates to certain improvements in shoes commonly known as "football" shoes in which cleats or spurs are usually fastened to the under side of the sole to prevent slipping of the wearer particularly in moist fields, and while I am aware that various forms of cleats or spurs secured by screws to metal plates incorporated in the sole of the shoe have heretofore been proposed, I believe that I am the first to provide conical cleats of circular cross section held in place with their larger ends against the under side of the sole by screws passing centrally through the cleats and engaged in threaded openings of thin metal plates which are secured to the upper face of the sole in such manner as to preserve the resiliency and flexibility of the sole and also to distribute the cleats or spurs in such manner as to afford a better grip upon the field than has heretofore been practised.

The main object, therefore, is to increase the gripping efficiency of shoes of this character and at the same time to reduce the suction and frictional resistance to withdrawal when embedded in soft earth such as wet clay or similar soil.

Another object in making the cleats conical and circular in cross section is to enable them to be self-cleaning and to reduce the liability of injury to other players by contact with the sides thereof.

A further object is to distribute the cleats or spurs in such manner as to assure a more accurate balance and greater rapidity of movement in running, starting, turning or stopping.

Other objects and uses relating to specific parts of the device will be brought out in the following description:

In the drawings:

Figure 1 is a perspective view of a shoe embodying the features of my invention.

Fig. 2 is a top plan of the detached sole and heel to which the cleats are secured

showing the manner of assembling the anchor plates for the cleats.

Fig. 3 is an enlarged longitudinal sectional view of the same sole taken on line 3—3, Fig. 2.

Figs. 4 and 5 are perspective views of the heel plate and one of the sole plates respectively.

Fig. 6 is a perspective view of one of the conical cleats or spurs.

Fig. 7 is a sectional view of a modified form of cleat-attaching screw and cleat.

As illustrated, the shoe comprises a main body commonly known as an "upper" —1— having its marginal lower edges stitched in any well known manner to an inner sole —2— which is provided with a welt —3— for securing by stitching to the main sole —4— having a heel portion —5— adapted to be fastened in any well known manner to the adjacent portion of the in-sole —2—, said main sole —4— and heel portion —5— being preferably made in a single piece of the best quality of sole-leather, the under side of which at the instep is skived away at —7— to give it greater flexibility at this point.

An extra sole —8— is secured along its marginal edges by the same stitching as —9— to the main sole —4— at the front of the instep for reinforcing purposes and also to afford a better support for the cleats or spurs presently described.

The heel portion of the main sole is also provided with a lift —10— nailed or otherwise secured to the adjacent heel portion of the main sole, and together with the extra sole —8— is made of heavy sole-leather of good wearing qualities.

The extra sole section —8— and heel lift —10— are important in shoes of this type in resisting the upward pressure of the several cleats against the inner sole and foot of the wearer, while the cleats themselves are secured to the under side of the extra sole —8— and heel-lift —10— in such manner as to distribute the upward pressure of each more evenly over the entire surface of the sole and heel without adding excessive weight or using an excessive number of the cleats, which when secured in operative position also serve to secure the extra sole —8— and heel-lift —10— to the adjacent portions of the main sole —4—.

The cleats as —11— are of substantially

- the same form and size for inter-changeability from one part to another of the shoe, and for lightness, strength and durability are preferably made of vulcanized fiber in 5 the form of truncated cones of circular cross section to avoid sharp corners and thereby to reduce the liability of injury to other players, who may accidentally come in contact therewith.
- 10 These cleats or spurs —11— together with the extra sole —8— and heel-lift —10— are preferably fastened to the main sole —4— prior to the securement of the latter to the insole —2— and may, therefore, constitute 15 a distinct article of manufacture to be applied to various forms and styles of "uppers" as —1—, the heel being usually provided with a pair of the cleats arranged side by side in spaced relation substantially mid-way between the front and rear edges of the 20 heel to bring the bearing or support more nearly in vertical alinement with the center of gravity of the wearer when resting upon the heels.
- 25 The sole is provided with a series, in this instance five, of the cleats or spurs —11—, one of which is arranged close to the toe of the sole and substantially mid-way between opposite sides thereof, while the 30 others are arranged in pairs, those of one pair being located side by side in transversely spaced relation just at the front of the instep, while those of the other pair are arranged side by side in transversely spaced 35 relation directly under the ball of the foot or substantially mid-way between the front cleat and rear pair of cleats.
- The two pairs of cleats directly in front of the instep and under the ball of the foot 40 also the two cleats on the heel afford a firm, square support for the user when standing, while the single front cleat near the toe provides a means for a quick "get away," the two cleats at the heel providing means 45 for a quick "stop."
- The entire system of cleats arranged, as described, serves to distribute the supporting points in such manner as to balance the user in practically any position he may assume without undue pressure upon any particular part of the foot.
- The means for securing the heel cleats to 50 the under side of the heel consists of a thin steel plate —12— having a series of, in this instance four, radially projecting arms arranged in pairs, those of each pair being diametrically opposite each other, one pair of arms as —13— being secured by rivets —14— to and through the adjacent heel 55 portion of the main sole —4—, while those of the other pair of arms as —15— are provided with pendent hollow bosses —16— extending through registering apertures —17— in the heel portions —5— and 60 —10—, and threaded internally for engage-

ment by threaded ends of screws —18— which are passed through central apertures —19— in the heel cleats —11—.

The lower ends of the screw openings —17— are preferably enlarged or counter sunk to receive the heads of the screws above the lower faces of the cleats when the latter are firmly secured in place, under which conditions, the heel portions —5— and —10— will be firmly clamped together 75 between the larger ends of the cleats and metal anchor plate —12—.

The means for clamping each of the sole cleats in place consists of a T-shaped steel anchor plate —20— having the intermediate 80 portion of its stem —21— and the outer ends of its head —22— secured by rivets —23— to the upper face of the main sole —4—, the central portion of the head of each of the anchor plates —20— being provided with a 85 pendent hollow boss —24— projecting through registering apertures —25— in the sole portions —4— and —8— and threaded internally for receiving the threaded end of a screw —26— similar to the screw —18— 90 in that it is provided with a head engaging in a counter sunk lower end of the corresponding cleat above the lower end face thereof, thereby providing a marginal flange on the lower end of each cleat surrounding the screw head and protecting the latter against undue wear, while at the same time the sockets in which the heads of the screws are seated serve as small cups to reduce the liability of slipping when in engagement with harder ground. 95

The larger ends of the several conical cleats are substantially flat to rest flatwise against the under side of the extra sole —8— and heel-lift —10— and when secured in place by the screws —26— coöperate with their respective anchor plates —20— and —12— to clamp the extra sole —8— and lift —10— to the main sole —4—, the vertical depth of the hollow bosses 100 —16— and —24— being slightly less than the combined thickness of the main sole —4— and extra lifts or pieces —8— and —10—, and, therefore, terminate slightly above the lower faces of said extra pieces to 105 enable the cleats to be withdrawn tightly against the lower faces thereof.

Making the cleats circular in cross section and conical longitudinally not only renders them self-cleaning from mud in 110 which they may become embedded but also facilitates their withdrawal therefrom against suction and frictional resistance incidental to their becoming embedded in the mud or clay and also reduces the liability of 115 injury to other players in case they may come in contact with the surfaces of the cleats, all of which add greatly to the efficiency and desirability of a shoe equipped with cleats of this character. 120 125 130

A relatively thin flexible metal plate —40— is applied to the upper surface of the instep of the main sole between it and the inner sole to add additional support for the arch of the foot without destroying the flexibility of the instep. In assembling the various parts, the anchor plates with the hollow bosses thereon are first riveted to the sole and heel portions of the main sole with 10 the internally threaded hollow bosses projecting downwardly through and slightly beyond the apertures therein to enter the registering apertures in the extra sole and lift of the heel after which the cleats may 15 be securely attached to the lower faces of the extra sole and heel-lift by means of their respective screws to hold them in place ready for stitching the main sole including the extra sole to the welt and inner 20 sole, and also for nailing the heel-lift to the heel portion of the main sole.

the under side of the heel portion and provided with apertures registering with the 30 first named apertures and frusto-conical spurs having their larger ends flat and bearing against the under side of the heel and provided with central upwardly projecting 35 threaded members screwed into the internally threaded bosses, an extra sole applied to the lower face of the main sole portion, a series of relatively thin metal plates secured to the upper face of the main sole portion in spaced relation and provided 40 with hollow bosses projecting upwardly through apertures in the main sole portion, said extra sole being provided with apertures registering with those in the main sole portion, and separate conical studs having their larger ends flat and engaged with the under side of the extra sole and provided with upwardly projecting threaded members screwing into the hollow bosses.

In witness whereof I have hereunto set 50 my hand this 21st day of April 1921.

JOSEPH KARL SCHWARZER.
